Norton Company, Worcester, Mass., a corpora-
tion of Massachusetts

Application December 14, 1939, Serial No. 309,173

5 Claims. (Cl. 51—34)

The invention relates to honing machines, and more particularly to a machine adapted for honing small internal bores or holes, such as the crankpin end bearing of an automobile connecting rod. This is a continuation-in-part of my copending application Serial No. 267,465, filed April 12, 1939.

One object of the invention is to provide a simple and thoroughly practical internal honing machine in which a small internal cylindrical bore may be rapidly honed to a surface of the desired quality. Another object of the invention is to provide a hole-lapping or honing machine in which the work piece, such as an automobile connecting rod, is held stationary and the honing tool is reciprocated longitudinally by means of a hydraulically operated fluid motor. A further object of the invention is to provide a honing machine for small cylindrical bores in which the honing tool is reciprocated longitudinally by means of a pair of fluid motors which are arranged on diametrically opposite sides of the honing tool. Another object of the invention is to provide a honing machine with a hydraulically reciprocated honing tool which is reciprocated longitudinally during the honing operation, in which an indexing mechanism actuated in timed relation with the longitudinal reciprocation serves to produce a partial rotation of the honing tool during each reciprocation of the tool. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of the invention,

Fig. 1 is a plan view of the improved honing machine, having parts broken away and shown in section to more clearly show the operating mechanism;

Fig. 2 is a diagrammatic showing of the fluid pressure system together with the honing machine;

Fig. 3 is a cross-sectional view, on a reduced scale, taken approximately on the line 3—3 of Fig. 1;

Fig. 4 is a fragmentary cross-sectional view, on a reduced scale, taken approximately on the line 4—4 of Fig. 1;

Fig. 5 is a cross-sectional view, on an enlarged scale, taken approximately on the line 5—5 of Fig. 1, showing the cam for expanding and contracting the honing tool;

Fig. 6 is a fragmentary sectional view taken on the line 6—6 of Fig. 5;

Fig. 7 is a fragmentary left-hand end elevation of the movable outboard bearing member shown in Fig. 1; and

Fig. 8 is a fragmentary elevation, on an enlarged scale, of the adjustable cam and index pawl actuating mechanism.

The improved honing machine as illustrated may comprise a base 10 having an upwardly extending frame 11 which is provided with a cylindrical bore 12. The frame 11 and bore 12 serve as a support for a horizontally extending member 13. The member 13 is provided with an integral hub 14 which is arranged to fit within the bore 12 of the frame 11. The member 13 and its integral hub 14 are held against rotation within the frame 11 by means of a key 15 and held in adjusted position on the frame 11 by means of a collar 16 which is screw threaded onto the hub portion 14.

The hub portion 14 of the plate 13 is provided with a central bore 18 which serves as a slidable support for a lapping or honing tool 20.

The tool 20 comprises a longitudinally extending tubular member 21 which is provided with a plurality of longitudinally extending slots 22 to receive the abrasive, each of which is arranged to receive a honing element or bonded abrasive stick 23.

The abrasive sticks 23 are each supported or fastened to sheet metal clips 24. A wedge-shaped member 25 is supported on the opposite side of the clip 24 from the abrasive honing element 23 and has an inner tapered surface 26 which engages and mates with a frusto-conical member 27 by means of which the abrasive honing elements 23 may be expanded or contracted.

Each of the metal clips 24 is provided with hooked ends 28 and 29. A garter spring 30 surrounds the hooks 28 at one end of the honing sticks 23 and a garter spring 31 surrounds and engages the hooks 29 at the other end of the honing sticks 23.

The garter springs 30 and 31 serve to hold the surfaces 26 at all times in operative engagement with the frusto-conical member 27. If the frusto-conical member 27 is moved toward the left (Fig. 1), the garter springs will collapse or contract the abrasive honing sticks 23, and similarly if the frusto-conical member 27 is moved toward the right,

20
2530
3540
4550
55

the members 25 and the abrasive honing sticks 23 will expand outwardly against the tension of the garter springs 30 and 31 to expand the abrasive honing elements 23 as desired.

- 5 If desired, the tubular portion 21 of the honing tool 20 may be provided with a bearing support on the opposite side of the honing elements 23. The base is provided with an upwardly extending bracket 35 having a bearing 36 mounted therein 10 in axial alignment with the tubular member 21 to serve as an outboard bearing for the honing tool during the honing operation. The bracket 35 supporting the outboard bearing 36 is preferably removably mounted on the base 10 to facilitate loading of work pieces into the machine. The bracket 35 (Fig. 7) is provided with a dovetailed slideway 37 which mates with a correspondingly shaped surface formed on the upper surface of the base 10. A binder screw 38 serves 15 to clamp the bracket 35 in position and also serves to facilitate rapid removal of the bracket 35 after a honing operation has been completed.

A spool-shaped member 40 is non-rotatably mounted on the end of the tubular member 21 25 and serves as a support for a plate 41 by means of which a reciprocatory movement is imparted to the honing tool 20. A pair of fluid motors 42 and 43 are arranged on diametrically opposite sides of the honing tool 20. The motors 42 and 30 43 are identical in construction and are fixedly mounted on the plate 13. Only one of these motors has been illustrated in detail, since they are identical in construction. The fluid motors comprise a cylinder 44 having a slidably mounted 35 piston 45 therein. A piston rod 46 is connected to the piston 45 and extends through opposite ends of said cylinder. One end of the piston rod 46 passes through the plate 13 and the plate 41 and is held in fixed relation to the plate 41 by a pair of nuts 47 and 48 which are screw threaded onto a threaded portion 49 of the piston rod 46. Similarly, the fluid motor 43 comprises a cylinder 44a having a slidably mounted piston 45a therein. A piston rod 46a is connected to the 40 piston 45a and extends through opposite ends of said cylinder. One end of the piston rod 46a passes through the plate 13 and the plate 41 and is held in fixed relation to the plate 41 by a pair of nuts 47a and 48a which are screw threaded onto a threaded portion 49a of the piston rod 46a. It will be readily apparent from the foregoing disclosure that when the nuts 47, 48 and 47a, 48a are locked in adjusted position, a reciprocatory motion of the pistons 45 and 45a will transmit 55 a corresponding reciprocatory movement through the plate 41 and tubular member 21 to reciprocate the honing elements 23 of the honing tool 20 relative to a work piece 50 to be honed.

A control valve is formed within the motor casing 42 and may comprise a pilot valve 51 which slides longitudinally within a valve sleeve 52. A reversing valve 53 is preferably in the form of a shuttle valve which is arranged to slide within a central aperture within the pilot valve 51. An 60 adjustably mounted collar 54 on the piston rod 46 is arranged in the path of a pair of adjustably mounted collars 55 and 56 which are carried by a pilot valve stem 57. Fluid under pressure from a fluid pressure system to be hereinafter 65 described enters through a pipe 58 (Fig. 2) into the valve mechanism and fluid is exhausted from a port 59 located on the opposite side of the cylinder 44.

The fluid motor 43 is similarly provided with a 70 control valve consisting of a pilot and reversing

valve (not shown) which are identical with the valve mechanism for the motor 42 above described. The piston rod 46a is provided with an adjustably mounted collar 54a which is arranged in the path of adjustably mounted collars 55a 5 and 56a which are supported on a pilot valve stem 57a and serve to actuate the pilot valve in timed relation with the movement of the piston 45a and the piston rod 56a.

A fluid pressure system is provided to convey 10 fluid under pressure to the fluid motors 42 and 43 synchronously to actuate the pistons 45 and 45a thereof to transmit a reciprocatory movement of the honing tool 20 relative to the work piece 50. This fluid pressure system may comprise a fluid 15 reservoir 65. A motor driven pump 66 draws fluid through a pipe 67 from the reservoir 65 and passes it simultaneously through the pipes 58 and 58a to the fluid operated motors 42 and 43, respectively, to produce a reciprocatory movement thereof. Fluid exhausting from the motors 42 and 43 passes out through the pipes 59 and 59a, respectively, to exhaust the fluid into the reservoir 65. A fluid pressure relief valve 68 is connected in the pipe lines 58 or 58a and 20 25 serves to convey excess fluid under pressure back to the reservoir 65.

A readily accessible means is provided for adjusting the position of the abrasive honing elements 23 relative to their axis of rotation so that 30 they may be readily expanded to hone a hole or bore to the required predetermined size. The frusto-conical shaped member 27 is preferably formed integral with a rod 70 which is journalled at the left-hand end (Fig. 1) in a bushing 71 35 which is screw threaded into the end of the tubular member 21. The other end of the rod 70 passes through a clearance hole in a bushing 72 which is screw threaded into the other end of the tubular shaped member 21. A spring 73 surrounds the rod 70 and is interposed between the frusto-conical member 27 and the bushing 72. The compression of the spring 73 normally tends to move the frusto-conical member 27 toward the left. A threaded portion 74 is provided on the rod 70 and an adjusting nut 75 is provided whereby the rod 70 may be adjusted in an endwise direction to either expand or contract the honing elements 23 as desired. A lock nut 76 serves to lock the nut 75 in adjusted position.

A readily accessible adjusting means is provided for rapidly expanding or contracting the honing elements 23 before and after a honing operation. The bushing 72 is provided at its outer end with an enlarged end portion having a cylindrical face 78 which serves as a rotatable support for a manually operable control handle 79. A cam face 80 is provided on the outer end face of the bushing 72 and a corresponding cam face 81 is provided on the inner face of the lever control handle 79. These two cam faces 80 and 81 are arranged so that when the handle is turned to permit a collapsing of the lap, the cam 81 is manually rotated relative to the cam 80 until the high points on the cam 81 coincide with the low points of the cam 80, thus releasing the compression of the spring 73, which serves to move the frusto-conical member 27 toward the left (Fig. 1) whereby the lapping or honing elements 23 are contracted by the garter springs 30 and 31, respectively. The bearing bracket 35 and the work piece 50 may then be removed and replaced with a new work piece. After a new work piece has been inserted in position, the handle 79 may then be actuated to cause an endwise movement

of the frusto-conical member 27 toward the right (Fig. 1) to expand the abrasive honing elements 23 into operative engagement with the bore or hole to be honed.

It is desirable that the honing tool 20 be given a slight rotary motion during its longitudinal movement so that the abrasive grains of each of the abrasive honing sticks 23, instead of traveling in a path parallel to the axis of the hone, will 10 travel in a path at an angle thereto, namely in a helical path. In order to produce the desired rotary movement of the honing tool 20, an indexing mechanism is provided which is actuated by and in timed relation with the reciprocatory movement of the honing tool 20 to produce a rotary or indexing movement of the honing tool on each stroke. A ratchet wheel 90 is fixedly mounted on the spool-shaped member 40 to produce a rotary movement of the honing tool 20. A pawl 91 is pivotally mounted on a stud 92. The stud 92 is fixedly mounted on an oscillatable arm 93 which is oscillatably supported on the sleeve 21. The arm 93 is arranged so that it reciprocates with the sleeve 21 during the reciprocation of the honing tool 20. An adjustable stop screw 94 is supported in an upwardly extending boss 95 formed integral with the plate 13 and serves to limit the swinging movement of the arm 93 in a counter-clockwise direction (Fig. 4). A spring 96 is connected at one end to the arm 93 and at the other end to a stud 97 which is fixedly supported on the frame or plate 13. A cam 98 is formed on a bracket 99 which is adjustably fixed to the plate 13 by means of screws 100 and 101 which pass through elongated slots in the bracket 99 and are screw threaded into the plate or frame 13. It will be readily apparent from the foregoing disclosure that when the honing tool 20 together with the ratchet wheel 90 and pawl 91 and arm 93 are moved toward the frame or plate 13, the arm 93 rides down the face of the cam 98. This movement serves to rock the arm 93 in a clockwise direction, thus transmitting an oscillating motion through the pawl 91 to rotate the ratchet wheel 90 together with the honing tool 20 one or more teeth at each stroke of the tool in the direction toward the left (Fig. 1).

It is desirable that a rotary movement be transmitted to the honing tool on each stroke of the tool. In order to accomplish this result, a second indexing pawl 105 is provided. The pawl 105 is supported on a stud 106 which is carried by an oscillatable arm 107. The arm 107 is oscillatably supported on the sleeve 21 and is held against endwise movement by a flange 108 on the sleeve 21. The arm 107 is normally held in engagement with an adjustable stop screw 109 which is screw threaded 60 into a boss 109 fixedly mounted on the frame or plate 13. One end of a spring 110 is connected to the arm 107 and the other end is connected to a stud 111 which is fixedly mounted on the plate or frame 13. A cam 112 is formed integral with a bracket 113. The bracket 113 is adjustably supported on the plate or frame 13 by means of screws 114 and 115. The screws 114 and 115 pass through elongated slots formed in the bracket 113 and are screw threaded into the plate or frame 13. By manipulation of the screws 114 and 115, the bracket 113 may be readily clamped in adjusted position and serves to facilitate adjustment of the cam 112. When the honing tool 20 moves toward the right 70 (Fig. 1), the arm 107 rides up the cam 112 (Fig.

8) which moves the arm 107 in a clockwise direction (Fig. 4) to rotate the ratchet wheel 90 one or more teeth to impart a rotary movement to the honing tool 20. It will be readily apparent from the foregoing disclosure that the index pawl 91 will impart a rotary movement to the ratchet wheel 90 when the honing tool is moved toward the left (Fig. 1) and the pawl 105 will transmit a rotary movement to the ratchet wheel 90 when the honing tool 20 is traversed 10 toward the right (Fig. 1) so that a partial rotation of the hone 20 is obtained at each traversing movement of the hone 20.

The machine illustrated in the drawings has been shown as particularly applicable to honing the crankpin ends of automobile engine connecting rods. These rods vary in length and it is desirable to provide a support for the work piece 50 which may be readily adjusted for accommodating any length of connecting rod. 20 The wristpin end 125 of the connecting rod 50 is supported by a pair of opposed centers 126 and 127 which are in turn supported by means of a pivotally mounted member 128 which is provided with a pair of integrally formed, upwardly extending arms 129 and 130 which respectively support the centers 126 and 127. The centers 126 and 127 are adjustably supported in their respective arms 129 and 130 and may be locked in adjusted position relative thereto 30 by means of clamping screws 131 and 132, respectively. The lower end of the frame 128 is pivotally supported on a shaft 135 which is journaled in spaced bosses 136 and 137 projecting upwardly from the base 10. The shaft 135 is 35 preferably fixed relative to the frame 128 and is rotatably supported in the bosses 136 and 137 to facilitate a rocking adjustment of the member 128. Clamping screws 138 and 139 are provided to lock the shaft 135 and the member 128 40 in adjusted position for honing a given length connecting rod.

The connecting rod may first be positioned relative to the hone 20 by taking off the end cap thereof and placing it around the cylindrical hone and then again clamping it in adjusted position, or a readily removable clamping member may be provided to clamp the lower half bearing in adjusted position for a honing operation. In the preferred construction, however, the outboard bearing 35 may be provided with a dovetailed slideway so that it is removably supported on the base 10 to facilitate loading of work pieces into the machine, in which case the work piece may be slid over the outer end of the tubular sleeve or member 21 and into an operative position on the hone 20 and with the wristpin end positioned between the supporting centers 126 and 127.

It is desirable to provide suitable adjustable 60 end thrust members for holding the crankpin end of the connecting rod 50 against endwise movement as the honing tool 20 is reciprocated. As illustrated in the drawings, this mechanism may comprise a pair of pivotally mounted arms 150 65 and 151 which are pivotally supported on a shaft 152 which is journaled in the upwardly extending portions 11 and 35a of the base 10. The arms 150 and 151 are each provided with an adjustable stop screw 153 and 154, respectively, which are screw threaded into the bosses formed in the upper ends of the arms 150 and 151. They are arranged to engage and locate and hold the crankpin end of the connecting rod 50 in adjusted position aligned with the centers 126 and 70 75

127 so as to prevent endwise movement of the crankpin end of the connecting rod during the honing operation. If desired, the honing machine may be operated either with or without 5 the use of the outboard bearing 35.

10 The operation of this honing apparatus is readily apparent from the foregoing disclosure. A work piece, such as a connecting rod 50, is inserted in place with its wristpin end supported by the centers 126 and 127 and its crankpin 15 end surrounding the abrasive honing sticks or elements 23 and held against endwise movement by adjustment of the stop locating screws 153 and 154 into engagement with the side faces 20 of the crankpin end of the connecting rod 50. The fluid pressure pump 66 is then started to reciprocate the honing tool 20 and the control handle 79 is then turned into the position illustrated in Fig. 1 to expand the abrasive honing 25 element 23 into operative engagement with the bore or hole to be honed. The honing operation may then be continued for the desired time interval, after which the hone may again be contracted or collapsed and the reciprocatory movement stopped to facilitate removal of the 30 finish honed piece of work and the insertion of a new piece thereinstead.

It will thus be seen that there has been provided by this invention apparatus in which the 35 various objects hereinabove set forth together with many thoroughly practical advantages are successfully achieved. As many possible embodiments may be made of the above invention and as many changes might be made in the embodiment above set forth, it is to be understood that 40 all matter hereinbefore set forth or shown in the accompanying drawings is to be interpreted as illustrative and not in a limiting sense.

I claim:

1. In a honing machine, a base, a rotatably 45 mounted hone thereon having a plurality of adjustable honing elements, means to expand or contract said elements, means to reciprocate said hone, and a work support for a connecting rod comprising a pair of aligned opposed work supporting centers to support the wristpin end of said rod while the crank end surrounds said honing tool.

2. In a honing machine having a base, a ro-

tatably mounted hone thereon having a plurality of radially adjustable honing elements, means to expand or contract said elements, means to reciprocate said hone, and a work support for an automotive connecting rod comprising a pair of aligned opposed centers to support the wristpin end of said rod while the crank bearing end of said rod surrounds said hole, and means to adjust the position of said centers so as to accommodate connecting rods of different lengths. 10

3. In a honing machine having a base, a rotatably mounted hone thereon having a plurality of radially adjustable honing elements, means to expand or contract said elements, means to reciprocate said hone, and a work support 15 comprising a pair of aligned opposed centers to support the wristpin end of a connecting rod while the crankpin bearing end surrounds the hone, a pivotal support for said centers, and means to adjust the position of said support so as to accommodate connecting rods of various 20 lengths.

4. In a honing machine having a base, a rotatably mounted hone thereon having a plurality of radially adjustable honing elements, means 25 to expand or contract said elements, means to reciprocate said hone, and a work support for an automotive connecting rod comprising a pair of aligned opposed centers to support the wristpin end of said rod while the crank bearing end 30 of said rod surrounds said hone, and means to hold the crank end of said connecting rod against endwise movement during the reciprocatory movement of said hone.

5. In a honing machine having a base, a rotatably mounted hone thereon having a plurality of radially adjustable honing elements, means to expand or contract said elements, means to reciprocate said hone, and a work support 35 for an automotive connecting rod comprising a pair of aligned opposed centers to support the wristpin end of said rod while the crank bearing end of said rod surrounds said hone, and means including opposed pivotally supported adjusting screws to locate and hold the crank end 40 of said rod against endwise movement during 45 reciprocation of said hone.

HERBERT S. INDGE.
